UNITED STATES PATENT OFFICE

2,538,233

ADJUSTABLE WALL PANEL

Charles K. Brandstrom, Seattle, Wash.

Application December 26, 1946, Serial No. 718,556

1 Claim. (Cl. 312—242)

1

This invention relates to drain boards and sinks and particularly to pivotally mounted shelves above the sinks for supporting dishes to be drained when in lowered position and to provide a part of the wall of the room above the sink when elevated.

In the operation and use of kitchens and sinks therein it is important to conserve space, and in the construction of most modern apartment houses relatively small areas for kitchens are provided. It is therefore frequently necessary to provide shelves for supporting dishes to be drained after having been washed in sinks, and it is also important to provide shelves which may be folded up into niches in the walls whereby the bottom of the shelves conform with and become a part of the wall.

It is therefore an object of this invention to provide in combination with the kitchen sink for washing dishes, a shelf above the same to be pivotally mounted in the wall of the room and adapted to be folded vertically into a niche of the wall, and adapted to be lowered horizontally to provide a shelf for supporting and draining dish water back into the sink together with means for sustaining the shelf in such alternate positions.

With these and other objects to be hereinafter stated I have illustratively exemplified my invention by the accompanying drawings, of which:

Figure 1 is a perspective and diagrammatic view of the shelf in lowered position with the wall.

Figure 2 is a cross section of the part shown in Figure 1 taken on line 2—2 thereon.

Figure 3 is a front elevation of the shelf folded upward into the niche in the wall with the outer surface or bottom of the shelf finished with square tiles to conform with similar squared tiling finish on the adjacent wall.

Like characters on the different figures represent like parts. The letter A represents generally any kitchen wall and the letter B represents generally a panel or shelf to support dishes or to be folded up flush with the wall vertically. Numerals 4 and 5 represent ordinary studs forming a part of a kitchen wall and 6 indicates any cross braces of any suitable material that may be mounted between the studs. 7 indicates any kitchen sink attached to the wall with a swing faucet 8 and hot and cold water controls 9. The numeral 10 indicates the bottom or lower side of the shelf B which in Figures 1 and 2 is shown in lowered position for supporting dishes over the sink after they have been washed therein. The tiling squares are generally represented by nu-

2

merals 11 being similarly arranged on both the wall and the bottom of the shelf, so that when the shelf is folded upward vertically they appear substantially as a unit or unbroken surface.

The marginal edges of the shelf are upturned to provide flanges 13 to prevent any drainage from dishes 12, spilling over such edges, and a small duct 14 is provided for draining any water from the dishes back into the sink. In some cases it may be desired to place any soft sheet of material 15 over the top of the shelf to prevent any injury to the edges of dishes when placed thereover. When such soft sheet is used it is advisable to locate the top of the duct level with the top of the sheet.

In order to prevent the lower edges of the dishes from sliding forward and to sustain them in leaning position against any rear wall 18 a plurality of ribs or rods may be placed on top of the shelf within the flanges, as indicated by rods 16, which may be adjustably sustained in position by a rotatable latch 28.

A niche 17 is provided in the wall between the studs, shown as numerals 4 and 5. Across this niche the shelf is mounted and supported by pins 19 and 20 extended longitudinally from the lower portions thereof and the outer ends rotatably disposed in the respective studs at each end of the shelf whereby the shelf may be folded upward in vertical position into the niche with the outer face thereof flush with the wall, and may be lowered outward horizontally for supporting the dishes. The pins being extended from the lower margins of the ends of the shelf in spaced relation from the rear edge thereof, the weight of the upper portion of the shelf when elevated will be back of or behind the pivot pins thus throwing the major portion of the weight of shelf behind the pins whereby the shelf will be sustained by gravity in vertical position when elevated but may be easily drawn forward and outward by a handle 21.

A pair of links are provided to sustain and control the bracket in extended position. The outer link 22 is connected by pivot pin 23 to one end of the shelf adjacent to the outer edge thereof, and an inner link 24 is connected by pivot 25 to the stud 4. The free ends of the links meet centrally and are connected together by a pivot pin 26; thus when the shelf is extended horizontally the two links assume a relatively straight line between the extended pivots 23 and 25 while the central pivot 26 is nearly on a dead center and so retains the shelf in horizontal position for supporting the weight of dishes there-

on. The inner link 24 is provided with a lip 27 near the outer end thereof which extends laterally over the top of link 22 when they are both folded down for sustaining the shelf horizontally and thus prevents the adjoining ends of the links from accidentally passing below a straight line whereby the outer edge of the shelf is prevented from folding upward when not so intended or desired. When the operator wishes to elevate the shelf manual pressure on the junction of the links below the pin 26 causes the links to fold upward as indicated by the dotted lines 22, when the shelf is in vertical position, and will there remain as sustained by gravity as before stated.

A narrow flange 29 is provided along the outer edge of the shelf, which prevents the outer face of the shelf from passing behind the face of the wall when folded vertically over the niche.

Having described my invention I claim as new 20 for Letters Patent:

An adjustable wall panel, including, a relatively flat frame for supporting dishes when lowered and for closing a niche between vertical wall studs when upraised, said frame having bars 25 along the sides for rigidity, together with means for supporting and operating the panel including, a pair of pins projected outwardly and lat-

erally from the bars for pivotal disposition in the respective studs, said pins being spaced from the inner ends of the bars a distance slightly less than the depth of the niche to provide a partial counterweight behind the pins to aid in lifting the panel and located adjacent to the lower edges of the bars for disposal of the greater portion of weight of the panel behind the pins when fully raised to automatically maintain the panel in such fully elevated position between the studs by the weight of the overhanging rear portion of the panel behind the pins and by gravity.
